(57) **CLAIM**

The ornamental design for a food tray as shown and described.

DESCRIPTION

FIG. 1 is a top, front perspective view of my food tray design.

FIG. 2 is a front elevational view thereof.

FIG. 3 is a rear elevational view thereof.

FIG. 4 is a left side elevational view thereof, the right side being a mirror image thereof.

FIG. 5 is a right-side elevation thereof.

FIG. 6 is a top plan view of the food tray of my design; and, FIG. 7 is a bottom plan view thereof.
